UNITED STATES PATENT OFFICE.

WILLIAM H. REIFF, OF PHILADELPHIA, PENNSYLVANIA.

PORTABLE BURGLAR-ALARM.

SPECIFICATION forming part of Letters Patent No. 225,641, dated March 16, 1880.

Application filed February 9, 1880.

To all whom it may concern:

Be it known that I, WILLIAM H. REIFF, of Philadelphia, in the county of Philadelphia and State of Pennsylvania, have invented a new and useful Improvement in Portable Burglar-Alarms, of which the following is a specification.

My invention relates to an improvement in portable burglar-alarms; and the invention 10 consists of a short barrel or cylinder of metal, within which is placed a piston attached to a rod that projects through a screw-cap at one end of the cylinder, and surrounding which rod is a spiral spring, which throws the piston forward after being contracted by the 15 drawing out of the piston-rod. The spring is retained in its contracted position as the piston-rod is drawn out by means of a spring- catch attached to the outside of the barrel and 20 engaging with a notch in the said rod. The spring-catch is detached from the piston-rod by means of a hook attached to a cord, by which the device is suspended from a door- frame, so that when the door is opened or 25 moved even slightly the device will drop to the extent of the length of the cord, thus releasing the piston-rod from the catch, when the piston is forced against a percussion-cap or cartridge placed in the opposite end of the 30 barrel, thus causing an explosion and creating an alarm.

Referring to the drawings, Figure 1 is a representation of my device attached to a door-frame and in position ready for use. Fig. 35 2 is a longitudinal section of the device.

a represents a cylinder or barrel of metal, of any desired size or caliber. *b* is a piston fitted to slide easily in the barrel *a*, and is attached to the rod *d*, that projects through the 40 screw-cap *r* on one end of the barrel *a*.

Surrounding the rod *d* is a spiral spring, *e*, which bears against the piston *b* and the screw-cap *r*, and serves to throw the piston forcibly forward after being contracted by the 45 drawing out of rod *d*. The rod *d* is held in its drawn-out position, as shown, by means of a spring-catch, *g*, which is attached to the outside of the barrel *a*, and, extending over the screw-cap *r*, engages in a notch or groove on 50 the rod *d*, as shown at *p*.

The rod *d* is released from its drawn-out position by simply detaching the spring-catch *g*, which is effected by means of a hook, *h*, one end of which is placed under the spring-catch

g, and is attached to a cord, *i*, which passes up through the ring *f* on the end of rod *d*, over a peg, *k*, which is inserted in the opening between the top of the door *A* and the frame *B*, and thence to a hook, *l*, screwed into the door-frame, as shown in Fig. 1. 55

The cap or cartridge is inserted in the barrel *a* at the opening *m*. The outer end or muzzle, *s*, is made of a less diameter than the main portion of the barrel, so as to afford a bearing for the cap or cartridge. 60

The cartridge is caused to explode by means of a pin or projection, *c*, on the piston *b*, which punctures the rim containing the fulminate. 65

The device may be used as a pistol by attaching a handle, *n*, as shown in dotted lines in Fig. 2, and arranging a trigger to release the spring-catch *g*. 70

When in use, the device is set with the rod *d* drawn out and held by the spring-catch *g*, 75 as shown. The releasing-hook *h* is then inserted under the spring-catch *g*. To the opposite end of hook *h* is attached the cord *i*, which passes up through the ring *f*, by means of which the device is held in a perpendicular 80 position. The cord *i* is then passed over a peg, *k*, inserted in the crevice between the door and the frame *B*, and fastened to a hook or other projection, *l*, in the frame, as shown in Fig. 1. Upon the slightest opening of the 85 door *A* the cord *i* will be released from the peg *k*, and as the device drops to the full length of the cord the hook or trigger *h* will release the spring *g* from the rod *d*, and the piston *b* will be caused to explode a cartridge 90 with which it comes in contact in the barrel.

What I claim as my invention, and desire to secure by Letters Patent, is—

A portable burglar-alarm consisting of a cylinder or barrel, *a*, provided with an opening, *m*, for the insertion of a cartridge, a piston, *b*, and rod *d*, actuated by a spring, *e*, in combination with a spring-catch, *g*, a releasing-hook, *h*, and cord *i*, by which the device is suspended from a door-frame, substantially 95 as and for the purpose set forth.

In testimony whereof I have signed my name to this specification in the presence of two subscribing witnesses.

WILLIAM H. REIFF.
